[57] CLAIM

The ornamental design for a locking device for an end clamp for metal wires, as shown and described.

DESCRIPTION

FIG. 1 is a bottom, rear perspective view of a locking device for an end clamp for metal wires showing my new design;

FIG. 2 is a top, front perspective view;

FIG. 3 is a side view taken from the left of FIG. 1;

FIG. 4 is a front view;

FIG. 5 is a top view;

FIG. 6 is a rear view;

FIG. 7 is a side view taken from the right of FIG. 2.

FIG. 1

FIG. 2

FIG. 3

FIG. 4

FIG. 5

FIG. 6

FIG. 7
